UNITED STATES PATENT OFFICE

1,940,034

COMMERCIAL AIR FILTER

Gordon Wallace, Wilmar, Calif.

Application August 8, 1931. Serial No. 555,906

1 Claim. (Cl. 183—10)

This invention relates to a commercial air filter particularly adaptable for relatively slow speed commercial engines, and the prime object of my invention is to provide a novel air filter which will effectively separate the dirt and sand from the incoming air before it passes into the motor.

Another object is to provide an air filter which can be easily and quickly cleaned and repaired when necessary.

A further object is to provide an air filter in which the incoming air is caused to strike a body of liquid at substantially right angles thereto and is subsequently passed thru a filtering material prior to the entrance of said air into the motor.

Other objects, advantages, and features of invention may appear from the accompanying drawing, the subjoined detailed description, and the appended claim.

In the drawing

Figure 1 is a transverse, sectional view of my filter.

Figure 2 is a sectional view taken at right angles to the position shown in Figure 1.

Figure 3 is a transverse, sectional view of the filter pack.

Referring more particularly to the drawing, the numeral 1 indicates a case closed at the top by a wall 2. A pan 3 fits over the bottom of the case 1 and is limited in its upward movement by a bead 4 formed on the case. The pan is held in position on the case by means of a pair of bails 5—5 which are hingedly secured at their upper ends to ears 6—6 secured to the case. A strap 7 is secured to the bottom of the pan 3, and the ends of this strap are bifurcated so as to receive the bails 5—5. A thumb nut 8 screws on to the bottom of each of the bails against the strap, thus holding the pan in position.

The pan is partially filled with oil or some other suitable liquid shown at 9, and the purpose of this oil is to collect the sand and dirt which is present in the air. An intake pipe 10 is centrally positioned in the case 1 and extends downwardly into the case through the top wall 2. The lower end of this pipe is crimped so as to constrict the lower end as shown at 11. The pipe 10 terminates either slightly above the liquid level or extends some what into the liquid.

The purpose of the constricted lower end of the pipe is to increase the velocity of the air which passes therethru. The air striking into the liquid causes a froth to be formed, which more effectively collects the dirt and sand. An

outlet pipe 12 extends from the case 1 adjacent the upper end thereof to the air intake of the engine.

To prevent the liquid from being drawn over into the engine, and also to further insure that all of the dirt will be removed from the air, I provide a filter pack 13 which comprises an outer ring 14 and a central sleeve 15. The sleeve 15 fits over the pipe 10 as shown in Figures 1 and 2. Screen rings 16—17 extend between the sleeve 15 and the ring 14 and at the top and bottom respectively of said ring.

A fibrous packing 18, such as hair, steel wool, or any other suitable material, is packed between the sleeve 15 and the ring 14. The air after impinging upon the liquid body, passes upwardly thru the filtering material and thence into the outlet pipe 12 to the engine.

A back fire relief valve 19 is provided in the top wall 2, and the valve is mounted on a stem 20 which is guided in a spider 21. The pressure caused by back firing of the engine will cause the valve to lift and the pressure will be relieved in the upper part of the case 1 instead of being transmitted downwardly to act upon the liquid 9.

The filter pack 13 is held in position by means of a spring ring 22 which fits into the bead 4 and this ring holds the filter pack against slipping downwardly. The pack is held against upward movement by butting against the inwardly extending bead 23.

Having described my invention, I claim:

An air filter comprising a case, a pan fitting over the bottom of said case, a pair of bales attached to the case, means on the pan engageable by the bales whereby said pan is removably held in position, a central, vertically extending intake pipe in said case, the lower end of said pipe being constricted, an outlet pipe adjacent upper end of said case, a filter pack within the case surrounding said intake pipe, said filter pack comprising an outer metal ring, a central sleeve closely fitting the intake pipe, said central sleeve projecting below the bottom surface of the filter pack whereby a hand hold is provided, a wire retaining screen at the top and bottom of the filter pack, a filter material between the wire screens, said case having a groove therein below the filter pack and a split ring in said groove bearing against the filter pack whereby said filter pack is held in position.

GORDON WALLACE.
